UNITED STATES PATENT OFFICE.

HENRY CHARLES WITZ, OF JOHNSTOWN, PENNSYLVANIA.

METHOD OF OPENING HARD OR FROZEN TAPPING-HOLES.

1,186,358.

Specification of Letters Patent.

Patented June 6, 1916.

Application filed February 17, 1916. Serial No. 78,935.

To all whom it may concern:

Be it known that I, HENRY C. WITZ, a citizen of the United States, and a resident of Johnstown, in the county of Cambria 5 and State of Pennsylvania, have invented a certain new and useful Improvement in Methods of Opening Hard or Frozen Tapping-Holes, of which the following is a specification.

10 My present invention relates generally to blast furnaces, open hearth furnaces, and the like, and more particularly to the tapping holes thereof, and aims to provide a simple, quick, and effective method of opening hard or frozen tapping holes.

15 The tapping holes of a blast or open hearth furnace as ordinarily closed by the plug usually used for this purpose, are subject to the disadvantage of the formation 20 of hard steel crusts at the inner portions of the tapping holes where the inner portions of the plugs in many instances are fused away, permitting a portion of the steel contents to find its way into the tapping hole 25 and form a hard crust or what is known as a frozen tapping hole. With the usual method of tapping holes, the task of breaking through this crust or frozen steel is laborious and expensive, and hence the object 30 of the present invention is to break through the crust quickly and effectively at a considerable saving in the cost of the operation, as well as the length of time required.

35 Referring to the accompanying drawings in which the means preferably utilized to carry out this method are illustrated, and which forms therefore a part of the present specification, Figure 1 is a sectional elevation of a portion of a blast furnace, adjacent to its tapping hole, and Fig. 2 is a central vertical section through a portion of the furnace on the center line of its tapping hole.

40 Referring now to these figures, I have generally indicated a blast furnace at A, 45 its tapping hole being seen at A' and being

in Fig. 1 closed by the usual plug B. As seen in Fig. 2, the inner portion of the plug B has been attacked by the fluid contents C of the furnace in such manner as to fuse 50 away the inner portion of the plug and admit into the inner portion of the tapping hole A', a portion of the material contents C, as seen at C' which, upon hardening, forms what is known as a frozen tapping⁵⁵ hole.

In order to break through the crust or hardened steel at C', I preferably utilize a heated member, such for instance, as an iron bar, as seen at D in Fig. 2, and continuously feed oxygen to the heated member so as to fuse the crust and in this way eat through the same. The oxygen is preferably delivered to the heated member in the form of a jet from a nozzle or pipe E⁶⁰ at one end of a flexible tube E', leading from an oxygen tank E² through valved connections, such as shown at E³ in Fig. 1.

Thus, by the means shown the heated member which, as above stated, may be in 70 a variety of forms, is after application as shown in Fig. 2, maintained in an incandescent state by the oxygen fed thereto, so as to eat its way through the crust at C' and thus complete the tapping operation. 75

It is to be understood that, while I have shown and described my improvements in connection with blast furnaces and steel, they are equally applicable and effective in connection with open hearth furnaces and 80 iron.

I claim:—

The herein described method of opening hard or frozen tapping holes, which consists in fusing the hard or frozen metal by 85 the application of a heated metal bar, and directing a jet of oxygen against the said bar.

HENRY CHARLES WITZ.
